(57) **CLAIM**

The ornamental design for a medical device connector, as shown and described.

DESCRIPTION

FIG. 1 is a top perspective view of a medical device connector;

FIG. 2 is bottom perspective view thereof;

FIG. 3 is a front side view thereof;

FIG. 4 is a bottom view thereof; and,

FIG. 5 is a back side view thereof.

The long dashed-lines represent the remainder of the article and do not form part of the claimed design, are directed to environment, and represent unclaimed subject matter.

The unshaded surfaces form no part of the claimed design. The short dashed-lines located on each pin of the medical device connector represent a boundary of the claimed design and form no part of the claimed design.
